BOTTLE SUPPORTING DEVICE

Philip R. Li Calzi, Moorestown, N. J.

Application April 30, 1945, Serial No. 591,213

2 Claims. (Cl. 248—105)

1

This invention relates to bottle supporting devices, and more particularly to a device for supporting a nursing bottle either in a position to facilitate feeding an infant or in a safe storage position.

When feeding an infant by means of a nursing bottle, it is customary either to hold the child in one's arm or lap, in which case the person feeding the child can direct the nipple to the baby's mouth, or to place the child on a suitable support, such as a bed, and arrange the bottle beside the child in a manner to enable the child to reach the nipple. In the former case, the substantially undivided attention is required of the person holding the child thereby frequently imposing hardships on a busy mother, for example. Where the child is laid down on a bed or the like and the bottle is propped up before it, usually with the aid of a pillow or folded blanket, so that the busy mother may be free to give some attention to her many other duties, the bottle frequently slips out of place with resulting annoyance to both child and mother. Moreover, in the latter case, the nipple is usually brought into contact with other objects which render it no longer sterilized. Neither of these methods, then, is entirely satisfactory, and especially so the latter one.

To remedy the difficulties involved in the second case, various bottle holding devices have been proposed heretofore. So far as I am aware, however, none of these has proven suitable for one reason or another. Thus, some have failed to fulfill adequately the intended purpose; some are quite complicated and expensive; and some have still other objectionable features.

The primary object of my invention is to provide an improved supporting device for nursing bottles which will be free from the aforementioned objectionable features of prior art bottle holders.

More particularly, it is an object of my invention to provide an improved nursing bottle holder which will support the nursing bottle in proper position, both as to height and angle, for suitably feeding an infant.

Another object of my invention is to provide an improved nursing bottle holder which will not only accommodate bottles of different sizes or diameters, but in which the position of the bottle can be easily and quickly adjusted to suit the requirements and comfort of any infant.

Still another object of my invention is to provide an improved nursing bottle holder which, when placed before a baby, will afford the child complete freedom of movement of arms, legs and head in a natural manner, and which will not obstruct the child's view.

A further object of my invention is to provide

an improved nursing bottle holder which will avoid rendering the nipple unsanitary by preventing the nipple from coming in contact with foreign objects once the bottle is mounted thereon.

Still a further object of my invention is to provide an improved nursing bottle holder in which a bottle may be mounted for safe transportation or storage without endangering either the bottle or its contents.

It is also an object of my invention to provide an improved nursing bottle holder as aforesaid which is extremely simple in construction, which is highly pleasing in appearance, which is very economical in cost, which can be used with complete safety to both the child and the bottle, and which is very efficient in use.

In accordance with my invention, the improved bottle supporting device comprises a base of such dimensions that it cannot be tipped or tilted readily, even when a bottle is mounted on the device, the base carrying a pair of relatively adjustable, upright clamping members between which the bottle may be clamped at any height and angle suitable for a particular child. Preferably, one of the upright members is adjustable on the base relative to the other upright member so that the spacing between said members can be varied to accommodate bottles of different diameters or widths. Also, the other upright member is preferably tiltably mounted for slight tilting movement relative to the first mentioned upright member whereby it can be brought into suitable bottle clamping relation with the first mentioned member in response to a manually operable control device associated with said clamping members. The upright members furthermore preferably extend above the base a distance greater than the height of a bottle and its nipple whereby the bottle may be received therebetween in upright or standing position. Thus, the bottle can be stored away safely for transportation without danger of its tilting over and breaking or losing its contents.

The novel features that I consider characteristic of my invention are set forth with particularity in the appended claims. The invention itself, however, both as to its organization and method of operation, as well as additional objects and advantages thereof, will best be understood from the following description of one embodiment thereof when read in connection with the accompanying drawing, in which

Figure 1 is a perspective view of a nursing bottle supporting device constructed according to my invention and showing a bottle mounted thereon for storage or transportation.

Figure 2 is a sectional view thereof taken substantially on the line II—II of Figure 1, and

Figure 3 is a side elevation thereof showing the bottle mounted in position for infant feeding.

Referring more particularly to the drawing in which similar reference characters designate corresponding parts throughout, there is shown a base 1 of large enough area so that it cannot be tipped or tilted easily about an edge thereof and provided with a pair of parallel slots 3. Adjustably mounted on the base 1 by means of screws 7 which extend through the slots 3 is a mounting block 5. The block or element 5 is adjustable on the base 1 toward and away from a second mounting block or element 9 which is secured to the base 1 in a fixed location by means of the screws 11.

Rigidly secured to the block 5 is an upright clamping member 13, the member 13 being held on the block 5 in any suitable manner, as by means of screws 15. A similar, upright member 17 is hingedly secured to the block 9 in any suitable manner, being arranged in opposed relation to the upright member 13. In the illustrated embodiment, the hinge connection between the upright member 17 and its mounting block 9 is effected by means of a pair of screws 19 which are received in slots 18 in the member 17 and are screwed into the block 9, the slots 18 being of slightly larger dimensions than the diameter of the screws 19. Thus, the member 17 can tilt slightly relative to the member 13 whereby it can be brought into bottle clamping relation with the member 13.

Secured to the upper end of the clamping member 13 is an elongated bolt 21 which extends through an opening 23 in the clamping member 17. A nut in the form of a knob 25 is threaded onto the protruding end of the bolt 21 and, when brought up against the member 17, forces the latter to tilt toward the member 13 to thereby clamp therebetween a nursing bottle 27. If desired, the members 13 and 17 may be made of somewhat flexible material and advantage taken of the resilience thereof to aid in clamping the bottle between them. For this purpose, the members 13 and 17, as well as the base 1, may be made of metal, wood, plastics, or any other suitable material. In any event, it will be seen that the bottle 27 can be placed between the upright clamping members 13 and 17 in any suitable, angular position and at any height along the members 13 and 17, as shown in Figure 3, to suit the needs and comfort of a baby who is to be fed, or it can be placed upright on the base 1 and clamped between the members 13 and 17, as shown in Figure 1, when the bottle is to be stored away or when it is to be transported, as in an automobile, for example. In either case, since the base 1 has a large area, it cannot be tipped over easily, and therefore the danger of losing the contents of the bottle or of the baby pushing it to one side or tipping it over is practically eliminated. At the same time, since the bottle holder is placed to one side of the baby, as clearly shown in Figure 3, the baby has complete freedom of movement of its limbs and head and its view is clear in practically all directions. This aids greatly in giving the baby considerable comfort during the feeding process and in giving the mother peace of mind and freedom to attend to her other duties while the baby is nursing.

Although I have shown and described but a single embodiment of my invention, it will undoubtedly be apparent that many other forms

thereof, as well as variations in the one described herein, are possible. For example, if desired, both of the members 13 and 17 may be tiltably supported on the base 1, and both of the clamping members may be made adjustable along the base 1 relative to each other instead of only the block 5 and its member 13 for the purpose of varying the spacing between the members 13 and 17 to enable them to accommodate bottles of different diameters. Again, other forms of manually operable devices for bringing the members 13 and 17 into bottle clamping relation may be employed in place of the particular one shown. Since my invention is susceptible to a great variety of forms and expressions, I desire to have it understood that I do not intend to be limited except insofar as is made necessary by the prior art and by the spirit of the appended claims.

I claim as my invention:

20. 1. A device for supporting a nursing bottle comprising a base, a pair of relatively movable upright members supported on said base in spaced relation to each other, the spacing between said members and the height thereof being sufficient to receive a bottle in standing position therebetween, said upright members being also adapted to receive said bottle therebetween in any angular position relative thereto and with the open end of said bottle extending laterally to one side thereof, and means for bringing said members into and maintaining said members in bottle clamping relation in any of said positions of said bottle.

2. A device for supporting a nursing bottle comprising a base, a first mounting element secured to said base in fixed position thereon, a second mounting element adjustably mounted on said base for adjustment relative to said first mounting element, means for releasably locking said second mounting element to said base in a selected position of adjustment thereon, a first upright member tiltably supported by said first mounting element, a second upright member rigidly supported by said second mounting element in opposed relation to said first upright member whereby said members are adapted to receive a bottle therebetween, said upright members being adapted to receive said bottle in either an upright position or in any one of a plurality of other positions angularly related thereto and with the open end of said bottle extending laterally to one side thereof, and means for tilting said first upright member relative to said second upright member to bring said members into and thereafter maintain said members in bottle clamping relation in any one or another of said positions of said bottle.
